KEY SELECTOR AND CONTAINER

Oliver Seely, Long Beach, Calif.

Application March 14, 1944, Serial No. 526,442

2 Claims. (Cl. 70—456)

1

This invention appertains to key holders, and has among its several objects the provision of a novel holder, or container, for carrying a number of keys in a convenient, compact, and orderly arrangement, in combination with a handy means, which is readily operable in a manner that any one of the keys can be quickly and easily selected and placed in a proper position for use, without interference from the other of the keys, or the usual difficulty of fumbling in the use of ordinary types of key holders.

With this and other objects and advantages in view, the invention resides in the certain new and useful combination, construction, and arrangement, of parts, as will be hereinafter more fully described, set forth in the appended claims, and illustrated in the accompanying drawing, in which:

Figure 1 is a side elevation of a single unit holder, in accordance with the invention.

Figure 2 is an end view.

Figure 3 is a vertical, longitudinal section, taken through the line 3—3 of Figure 2.

Figure 4 is a top plan view.

Figure 5 is a vertical, transverse section, taken through the line 5—5 of Figure 1.

Figure 6 is an end view of the selector elements per se;

Figure 7 is a side elevation, partly in section, of a modified, or double unit, form of the holder.

Figure 8 is a vertical, transverse section, taken through the line 8—8 of Figure 7.

Referring to the drawing, wherein like characters of reference denote corresponding parts in the several related views, and more particularly to Figures 1 through 6, the embodiment of the invention, as it is exemplified therein, is comprised in an elongated container body 11, formed of plastic, metal or other suitable material, which is machined or molded to the general shape of a key, in its side elevation. The body 11 is kerfed longitudinally outward from a point removed from its inner end to provide a plurality of parallel slots 12, that open through its outer end and partially through its lower side, inwardly from the outer end. The walls 13, forming the sides of the slots 12, are made circular in form at their outer ends, as at 14, to conform to the like ends of keys 15, positioned edgewise within the slots 12; a pivot pin 16 being passed centrally through the circular portions 14 and through the openings usually present in the like portions of the keys. The slots 12 are closed at the lower side of the body 11, by a bottom wall 17, which slopes upwardly and rearwardly from a point adjacent the

2

lower sides of the circular portions 14, of the walls 13. The inner ends of the slots 12 are closed off by a cylindrical wall portion 18, that is integral with the walls 13, 17. Thus, with the keys 15 lying within the slots 12, and their circular outer ends engaged on the pivot pin 16, the bit ends of the same rest on the slope of the bottom wall 17 at the inner ends of the slots.

Mounted for turning movement on the cylindrical end portion 18, of the body 11, is a cylindrical knob 19, which has a sleeve 20 extending from its inner side and enclosing the adjacent end portions of the slots 12 and the side walls 13, thus retaining the keys 15 within the slots. The sleeve 20 is slotted, at one point on its circumference, as at 21, so that, when the knob 19 is turned, the slot 21 can be selectively registered with any one of the slots 12 for the outward swinging movement of a key 15 on the pivot pin 16. With the slot 21 in registry with a proper slot 12, and turning the body 11 axially one hundred and eighty (180) degrees to position, the slots 12 and 21 in a downward direction, the key will, of its own accord, swing free of its respective slot on the pivot 16, so that it can be easily grasped and inserted into a lock. When not in use, the knob 19 is turned to position the slot 21 out of registry with the several slots 12.

To retain the knob 19 against accidental turning movements, and to otherwise hold it in any one of its several set positions, a detent 22, that may take the form of a steel ball, is seated in the open end of a radial bore 23, formed in the cylindrical end portion 18, of the body 11, and upon the end of a coiled spring 24, housed within the bore, which holds it in contact with the inner surface of the annular wall of the knob and forces it into engagement successively with a series of seats 25, opening through the annular wall. These seats 25 correspond in number to the number of the slots 12 and are spaced apart relatively thereto, so that the knob 19 is temporarily held against turning movement thereby, whenever the slot 21 is placed in registry with one of the slots 12. An additional seat 26 is also provided at a distance from the seats 25 for cooperation with the detent 22 to hold the knob 19 against accidental turning, when the slot 21 is displaced from registry with the slots 12, and the holder is not in use.

In order to assure of free passage of the bit of a key 15 outwardly and inwardly of the slot 21, in the sleeve 20, the inner and outer sides of the opposed edges of the sleeve, forming the sides of the slot, are beveled, as at 21', and as is best shown in Figure 6; the bevels acting to center

a key on the pivot pin 16 and relatively to the opposed walls of the slot 12, in which the key is normally housed. The knob 19 is held in place on the cylindrical portion 20, of the body 11, by a screw 28 passed inwardly through an opening 27 in its end wall for threaded engagement in the end wall of the cylindrical portion 20.

In the double unit form of the holder, shown in Figures 7 and 8, the key receiving slots 112 are kerfed in the top and bottom sides of a substantially triangular shaped body 111, which sides convergently slope inwardly from the outer end of the body and merge into the cylindrical portion 120 at the inner end of the body. The corners of the outer end of the body 111 are rounded, as at 114, to give to the side walls 113, separated by the slots 112, the general form of the keys 115, housed within the slots. A pivot pin 116 is passed through each rounded corner portion 114, at the centers thereof, for engagement through the openings usually present in the circular ends of the keys. A cylindrical knob 119 is rotatably mounted on the cylindrical portion 118, of the body 111, and a retaining screw 128 passed centrally inward through its end wall and threaded into the opposed end wall of the body portion 118. The knob 119 has its annular side wall provided with diametrically opposed sets of apertured seats 125, for the cooperation therewith of the detent 122, which is maintained in contact with the inner surface of the sleeve 120, extending forwardly from the engaged end of the knob 119, by the pressure of the coiled spring 124, housed in the radial bore 123, in the cylindrical end portion 118, of the body 111. Opening through the sleeve 120, at opposite points on its circumference, and midway between the sets of apertured seats 125, are like apertured seats 126, to be engaged by the detent 122, to retain the knob 119 against accidental rotative motion, when it is positioned to displace the key releasing slot 121, formed in the sleeve 120, out of registry with the several key receiving slots 112; the slot 121 having its edges beveled, as at 121' to facilitate the passage of the keys outwardly and inwardly of the slots 112, as before stated.

From this description, it will be obvious that the holders have the advantage of housing a number of keys in a manner that permits of a quick selection of one required for immediate use and, at the same time, prevents them from contacting the walls of a pocket, in which the holder is being carried, which contact, permitted by certain of other types of holders, causes wear and tear of the pocket walls. Also, the rotative knob, with its slotted sleeve, provides a quick and easily adjustable means for releasing the selected key to a position exteriorly of the holder for its ready insertion into a lock.

Having thus fully described my invention, it is to be understood that various changes in design

and minor details of construction to which the holders are found to be susceptible, may be resorted to, without departing from the spirit of the invention, or its scope as claimed.

5. What is claimed is:

1. A key holder comprising a body kerfed longitudinally to provide a plurality of equidistantly spaced parallel walls, the spaces between the parallel walls each constituting a receiving slot for a flat key, the slots opening through one end of the body, a pivot pin passed through the free ends of the parallel walls and engaged through the apertured ends of keys housed within the receiving slots, the end of the body connecting the opposite ends of the parallel walls being cylindrical and a cylindrical knob mounted for turning motion on the cylindrical end of the body and having a cylindrical sleeve encircled about the connected ends of the parallel walls to enclose the bit ends of the keys, the sleeve of the knob being formed with a slot of a width sufficient to pass but one key to release the bit end of a selected key when the knob is turned to place the release slot in registry with the receiving slot housing the selected key.

2. A key holder comprising a body made of plastic, metal, or other suitable material, kerfed longitudinally at one side to provide a plurality of equidistantly spaced parallel walls, the spaces between the parallel walls each constituting a receiving slot for a flat key, the slots opening through one end of the body, a pivot pin passed through the free ends of the parallel walls and engaged through the apertured ends of keys housed within the receiving slots, the end of the body connecting the opposite ends of the parallel walls being cylindrical, and a cylindrical knob mounted for turning motion on the cylindrical end of the body and having a portion encircled about the connected ends of the parallel walls to enclose the bit ends of the keys, the encircling portion of the knob being slotted to release the bit end of a selected key when the knob is turned to place the release slot in registry with the receiving slot housing the selected key, with a detent carried by the cylindrical end portion of the body for cooperation with a series of seats formed in the like portion of the knob to retain the knob in a set position, certain of the seats corresponding in number to the number of the key receiving slots and equally spaced apart with respect thereto, so that the knob will be held by the detent against accidental movement when set to align the key releasing slot with the receiving slot housing a selected key, another of the seats being spaced from the first named seats for its engagement by the detent to hold the knob stationary when the key releasing slot is positioned out of line with the receiving slots.

60 OLIVER SEELY.
